United States Patent Office

Des. 212,249
Patented Sept. 17, 1968

212,249

CLOCK

Walter B. Herbst, Evanston, and Ralph M. La Zar, Skokie, Ill., assignors to Sunbeam Corporation, Chicago, Ill., a corporation of Illinois

Original design application Feb. 20, 1967, Ser. No. 5,863.
Divided and this application Oct. 18, 1967, Ser. No. 9,302

Term of patent 14 years

(Cl. D42—7)

Fig. 1.

Fig. 2.

FIG. 1 is a part elevation view of a clock of our design; and

FIG. 2 is a sectional view taken along the section line 2—2 of FIG. 1.

The dominant features of the design are shown in solid lines.

This application is a division of co-pending application Ser. No. 5,863, filed Feb. 20, 1967.

We claim:

The ornamental design for a clock, as shown and described.
